[57] CLAIM

The ornamental design for a combined whistle, dial and rattle, as shown and described.

DESCRIPTION

FIG. 1 is a front, top and right side perspective view of a combined whistle, dial and rattle showing our new design.

FIG. 2 is a rear elevational view thereof;

FIG. 3 is a top plan view thereof;

FIG. 4 is a right side elevational view thereof, the left side being a mirror image thereof; and

FIG. 5 is a bottom plan view thereof.
